UNITED STATES PATENT OFFICE

159,875

FLOOR LAMP

Kurt Versen, Tenafly, N. J.

Application December 9, 1947, Serial No. 143,047

Term of patent 14 years

(Cl. D48—20)

To all whom it may concern:

Be it known that I, Kurt Versen, a citizen of the United States, residing at Tenafly, in the county of Bergen and State of New Jersey, have invented a new, original, and ornamental Design for a Floor Lamp, of which the following is a specification, reference being had to the accompanying drawing, forming part hereof.

In the drawing:

Fig. 1 is an elevational view partly in perspective of a floor lamp, with the lamp shade partly in section showing my new design,

Fig. 2 is a top view of the floor lamp of Fig. 1,

Fig. 3 is an elevational view partly in perspective of the lamp of Fig. 1 in a different position, and Fig. 4 is a like view of the lamp of Fig. 1 showing another different position and having the lamp shade rotated to an inverted position.

I claim:

The ornamental design for a floor lamp, substantially as shown.

KURT VERSEN.
